Patented June 6, 1922.

UNITED STATES PATENT OFFICE.

ANDREW HARILA, OF PARK CITY, UTAH.

ALTITUDE METER.

1,418,922.

Specification of Letters Patent. Patented June 6, 1922.

Application filed November 20, 1918. Serial No. 263,323.

To all whom it may concern:

Be it known that I, ANDREW HARILA, residing at Park City, in the county of Summit and State of Utah, have invented certain new and useful Improvements in an Altitude Meter, of which the following is a specification.

My invention relates to an altitude meter or apparatus to indicate distance from the earth.

Generally the invention aims to provide an improved, simple, inexpensive and efficient construction.

A prime object is to so construct the apparatus that it will efficiently function regardless of the position of the body upon which it is mounted or by which it is carried, for instance, an airship.

Another important object is to provide a device for the purpose mentioned having indicating means operable by atmospheric air pressure, and preferably being in the nature of an hermetic casing having rubber or other elastic portions to control the movement of the indicating means. Also I aim to provide protecting means for the elastic portions, and the otherwise detailed construction illustrated in accompanying drawing and described hereinafter.

30 Of one preferred embodiment, as illustrated in said drawings:

Figure 1 is a front elevation;

Figure 2 is a side elevation;

35 Figure 3 is a vertical sectional view on the line 3—3 of Figure 2;

Figure 4 is a transverse sectional view through the apparatus on the line 4—4 of Figure 3, and

40 Figure 5 is a fragmentary elevational view of one of the struts or supporting rods for the casing.

In carrying out the invention, a suitable form of casing is provided. However, as shown in the drawings, it is preferably shallow, and rectangular, although it may be of any other desired configuration. Said casing or box may have a front wall 6, a rear wall 7, a bottom wall 8 and a top wall 9, integral with each other, but of course may 45 be made separate if desired. Any suitable material may be used. These walls are preferably vulcanized or hard rubber and rigid. The casing also has side walls 10 and 11. These walls are also preferably made of 50 rubber, but in this instance, are elastic, so as to be capable of movement into the dotted

line position shown in Fig. 3. Since the remainder of the casing is made of hard rubber, these walls 10 and 11, may be vulcanized thereto so that the casing may be 60 hermetic.

The structure is preferably braced by diagonal struts or rods 12 which have at each end, an anchor or arm 13, to be embedded in the hard rubber of the casing, at 65 the junction of walls 8 and 9 and 10 and 11 as shown in Fig. 3. These struts cross each other, and at their centers, are provided with aligned eyelets 14. A removable bolt 15 extends through the eyelets 14 and also 70 through an eyelet 16, of a pointer 17, in order to pivotally mount said pointer. Means is provided whereby the pointer 17 will be moved according to the elastic movement of the walls 10 and 11. To this end, links 18 75 and 19, are pivoted to the pointer 17 as at 20, one being pivoted above the pivot 16 while the other is pivoted below it. Any suitable means may connect the rods 18 and 19 to the walls 10 and 11, for instance 80 sockets 21 of hard or vulcanized rubber, vulcanized to the walls 10 and 11, and pivotally mounting balls 22 into which the links 18 and 19 may screw or otherwise fasten.

Co-operating with the pointer 17, at the 85 arrow 18 thereof, is an arcuate dial 23, fastened in any suitable manner and for instance having its terminals 24, bent and clinched around the struts 12. Suitable indications are delineated upon the dial as 90 shown, to indicate distance in feet, from the earth.

In order that the meter may be read, that is the relative position of the arrow and the dial 23 observed, a suitable window is provided in the front wall 6, being closed by a transparent panel 25, which may be a magnifying glass.

In order to rigidify the structure, and guard the walls 10 and 11, suitable guard 100 walls or plates 26, are formed integrally with the casing, being spaced from the walls 10 and 11, by connecting portions 27. In order that the air may effectively reach the elastic walls 10 and 11, said guard walls 26 105 are preferably foraminous or perforated, as shown.

It will be understood, that the walls of the casing, namely 6, 7, 8, 9, 10 and 11, are hermetically connected together, and that 110 the joint between the panel 25 and wall 6 is also hermetic. Thus all of the operating

parts or indicating mechanism are maintained within an hermetic closure.

In operation, say the device is carried by airship or otherwise elevated to 8,000 feet from the earth. In such an instance, the pointer 17 will be in the position shown in Fig. 3 and the elastic walls 10 and 11 will be in the position also shown at said figure, or at rest, with the pressure within the casing equal to the atmospheric pressure. As the apparatus varies its height, the elastic walls 10 and 11 will yield as suggested by the dotted lines in Fig. 3, accordingly shifting the links 18 and 19 and the pointer 17 on its pivot 16 and to the proper indication on the dial 23. Since the device depends upon the atmospheric pressure, it does not necessarily have to be held in any certain position, and accordingly will under all conditions, effectually function.

Since merely the preferred embodiment of the invention has been illustrated and described, it is to be understood that the details of construction, material and sizes of the parts may be varied within its spirit and scope as defined by the appended claims.

I claim:

1. An indicator of the class described having a hermetically closed casing, elastic side walls, indicating mechanism mounted on the casing, means connecting said elastic walls to said indicating mechanism, and guarding means rigid with the casing covering said elastic walls.
2. An indicator of the class described having a hermetically closed casing, bracing rods for the casing, indicating mechanism mounted on said rods, said casing having yielding-to-pressure side walls, and operating means connected to the indicator and yielding-to-pressure walls to show the force exerted on said yielding walls.
3. An indicator of the class described having a hermetically closed casing, bracing rods for the casing, indicating mechanism mounted on said rods, said casing having yieldable parts, and operating means connected to the indicator and yieldable parts, said rods being disposed in crossed relation and at their ends being secured to the casing.
4. An indicator of the class described having a hermetically closed casing, bracing means for the casing, a pointer mounted on the bracing means, a scale plate with which

the pointer cooperates, said casing having 55 movable side walls, and links movable by said walls, said links being movably connected to the indicator.

5. An indicator of the class described having a hermetically closed casing, a pointer within the casing, a scale with which the pointer cooperates, said casing having yieldable side walls, socket members secured to the walls, balls mounted in the socket members, and links extending from the balls, said links being movably connected to the indicator.

6. An indicator of the class described having a hermetically sealed casing, bracing means for the casing comprising intersecting 70 rods, a pointer pivoted to the rods at their junction, a dial secured to the rods at a distance from the junction, said pointer being movable, and means associated with the pointer to impart movement thereto.

7. An indicator of the class described having a hermetically sealed casing, said casing having yieldable walls, bracing means for the casing, indicating means within the casing having a pointer member, said member 80 being pivoted to the bracing means, and links extending from said walls, said links being pivoted to the pointer member on opposite sides of its pivot.

8. An indicator of the class described having a hermetically sealed casing, elastic walls for said casing, said casing being made of rubber, said walls also being made of rubber and vulcanized thereto, guard walls integral with the casing to protect the said elastic walls, brace rods within the casing disposed in crossed relation and having anchors embedded in the casing at their ends, a pointer member pivoted to said rods at their junction, a dial associated with said pointer member connected to the rods at a distance from said junction, sockets secured to said elastic walls, balls mounted in said sockets, links extending from said balls, and means pivoting said links to the pointer member 100 on opposite sides of its pivot.

In testimony whereof, I have affixed my signature in the presence of two witnesses.

ANDREW HARILA.
